UNITED STATES PATENT OFFICE

WALTER S. ADAMS, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

CAR-TRUCK.

1,077,026.

Specification of Letters Patent.

Patented Oct. 28, 1913.

Application filed August 16, 1912. Serial No. 715,318.

To all whom it may concern:

Be it known that I, WALTER S. ADAMS, a citizen of the United States, residing in the city and county of Philadelphia, State of Pennsylvania, and whose post-office address is care of The J. G. Brill Co., Sixty-second street and Woodland avenue, in said city, have invented certain new and useful Improvements in Car-Trucks, of which the following is a specification.

My invention has relation to car trucks, and the specific object of my invention is to improve the support of the truck-frame or car body on the axle boxes or axle.

The object of my present invention is to render the support of the truck-frame on the running gear or axle boxes, as the case may be, more stable longitudinally and transversely, and more flexible than usual, and to relieve the said parts from strain due to lateral jars. The improvements allow of a swinging movement transversely of the truck between, the truck frame and axles etc., so as to cushion the blows imposed on the wheels and boxes on striking curves etc., and this is effected by providing for a lateral and relative movement between the frame and axle boxes, and the absorption of that movement by links so arranged that their arc of oscillation is restrained by or through the superimposed car weight. These, and other, results are secured by the construction herein shown and described, which embodies one form of my present invention.

In the drawing forming part of this specification, Figure 1 is a side elevation of a portion of a car truck embodying my improvements. Fig. 2 is a plan view of Fig. 1. Fig. 3 is an end elevation of Figs. 1 and 2. Fig. 4 is a sectional elevation on the line *a—a* of Fig. 2, looking in the direction of the arrows. Fig. 5 is an enlarged plan view of the axle box. Fig. 6 is a front elevation of Fig. 5, parts being broken away shown in section to more clearly illustrate the construction. Fig. 7 is a side elevation of the axle box. Fig. 8 is a plan view of the stirrup seat. Fig. 9 is a sectional elevation of the same, taken on the line *b—b* of Fig. 8, looking in the direction of the arrows. Figs. 10 and 11 are respectively a front elevation of a modified form of stirrup link support and a section on the line *c—c* of Fig. 10, looking in the direction of the arrows, and

Figs. 12 and 13 are respectively front and plan views of one end of the axle box frame.

As above suggested, the improvements may be embodied in trucks otherwise constructed, but they are especially designed for application and use to the four-wheeled non-pivotal type of truck illustrated. I therefore will describe them in connection with a structure generally of that character; deeming that it is only necessary here to show and describe that portion which is immediately adjacent the axle boxes. In this embodiment, 1 indicates an axle, 2 the car wheels, 3 the top chord, 4 the lower chord, 5 the spring-posts extending between and secured to the lower and upper chords, which spring posts pass loosely through side-bars 6 having axle-box yokes or pedestals 7 the arms 7^a of which surround the axle boxes 8, which yokes or pedestals lie between front and rear axle-box ears or projections 9 and 10, the yoke being capable of free lateral movement between the said ears, as shown in Fig. 2. The axle boxes may be constructed as shown or be of any approved design. The side bars 6 have extensions 11 and seats 12. The extensions may be connected transversely, if desired, to unite the side frames into a unitary structure, called the axle-box or stationary frame. A semi-elliptic or leaf spring 13 (part of which is shown in Fig. 1) may be secured upon the seats 12, their seats engaging guides 14 secured to the upper chord 3 as shown in said figure. It is intended that each of the devices to be described, the springs 13 etc., are duplicated at each of the axle-boxes.

Under the present improvements, the axle-box springs 15 are supported upon swinging connections or stirrups, which are in turn supported by the axle boxes, the construction being such as to provide efficient spring support of the axle box frame, to relieve it of the jar following its usual forcible contact with the axle boxes, and at the same time provide means whereby the movable portion of the truck frame, or the car body, or both, may have a movement generally longitudinally of the axes of the axle, without disturbing the spring support of the axle box frame upon the running gear. By this arrangement, the transverse impulses of the car body on the one hand, due to its operation, or those of the truck, due to its operation, which impulses very often

work in opposition to each other, are cushioned and modified, so that the unnecessary jars between the pedestals and axle boxes and the unnecessary strains between the 5 spring posts and the axle box frame are avoided and the general operation of the truck under the influence of motor propulsion or braking, are considerably improved.

The axle boxes 8 are provided with the 10 ears 9 and 10, preferably cast integrally with the axle boxes, the outward projection of the front ears being greater than that of the inner ears, so that the stirrup of swinging connection hereinafter referred to will lie at an angle to the longitudinal axis of the axle and converge outwardly therefrom in both directions. The ends of the ears are each provided with hemi-spherical seats 16, 17 and enlarged apertures 18, 19.

20 Indicated generally by the numeral 20 are the stirrup seats, comprising a casting having a central recess or depression 21 forming a spring-seat, an opening 22 through the base 23, a projection 24 on the 25 under side and at the end of the casting in which is formed a recess 25, and a coned aperture 26 in the end, as shown in Fig. 2, these stirrup seats are disposed at an angle to the longitudinal axis of the axle and converge toward the same.

At 27, 28 are the stirrup links, each provided at its upper end with a half-ball projection 29, 30, the latter being seated respectively in the seats 16, 17, the links passing 35 through the apertures 18 and 19, in the ends of the ears 10 and 9 respectively, and through the coned apertures 26 in the ends of the stirrup seats, which ends are provided with nuts 31, 32 and washers 33, 34, which 40 washers lie within the recesses 25 and engage the face 35 of the stirrup seat. The sides of the recess 25 are preferably extended out at an angle, as shown at 36, and the face 35 being slightly curved upwardly 45 as at 37, in order to provide for a slight oscillatory movement of the edges of the nuts 31, 32 or washers 33, 34 on the seats 35, 36. The stirrup seats are by this construction capable of swinging bodily without 50 disturbing the spring support of the axle box frame, the swing being limited and restrained by the lifting action of the ends of the stirrup links.

Instead of using the universal connection 55 shown in Fig. 4, and other views, for the support of the stirrup links, the modified form shown in Figs. 10 and 11 may be employed, in which the axle box ear 38 is provided with apertured lugs 39 which 60 carry bolts 40 pivotally supporting stirrup links 41, which pass through the two-part aperture 42, 43 in the ends of the axle box ears.

The construction shown in Figs. 10 and 65 11 is intended to be otherwise constructed

as in Fig. 1, etc., and allows of the swinging of the stirrups only in one general direction; while that shown in the other figures allows of a substantially universal swing. As the former construction, however, will 70 measurably secure some of the advantageous results flowing from my improvements, I deem it necessary to illustrate this modified form. The spring posts 5 pass through widened apertures 44 formed in the enlargements 45 in the side frames and through the aperture 22 in the base 23 of the stirrup seat 20. By reference to Fig. 4, it will be seen that the car springs and axle box springs are located in the same general vertical plane or in alignment with each other. Surrounding the spring posts 5 are the main car-body springs 46. These rest upon spring seats 47, which in turn rest upon the enlargements 45 of the side bars, and the 75 side bars in turn bear upon the axle-box springs 15 through the medium of caps 48; the top chord 3 having the usual caps 49 bearing on the springs 48. The spring posts 5 also pass loosely through enlarged apertures in both the spring seats and caps 48.

The angular disposition of the stirrups relative to the longitudinal axis of the axle provides a greater distance between the stirrup supports than would be the case if the 95 stirrups were located parallel to the plane of the axle while the lengthening of this distance between the points of support is of advantage in securing the results flowing from this improved construction, such results may be had by the parallel disposition above referred to. While this angular disposition may be modified, say for instance by reversing the positions of the axle box ears, so that the stirrup seats diverge from 100 instead of converge toward the axle, I prefer the arrangement shown and described.

While I have shown a construction embodying the underlying principles of my improvements, I do not limit myself to the 110 same, as many of the results flowing from my invention can be secured by a construction differing from that disclosed; so I do not limit my invention to the exact structure shown and described herein, as the same 115 may be modified to suit particular cases without departing from the spirit of my invention.

I claim:—

1. In a car truck, the combination with 120 the axle boxes, diagonally disposed stirrups movably supported from the axle boxes, and a truck frame supported upon said stirrups.
2. In a car truck, the combination with 125 the axle boxes, diagonally disposed stirrups movably supported from the axle boxes, a truck frame supported upon said stirrups, and springs for supporting the truck frame on said stirrups.
3. In a car truck, the combination with 130

the axle and axle boxes, pairs of links supported at each side of the axle boxes, each pair carrying a spring seat, a spring attached to the seats, and a truck frame supported on said springs having yokes embracing the axle boxes.

4. In a car truck, the combination with the axle, axle boxes, pairs of links pivotally supported from the axle boxes at each side thereof, a spring seat on the links, a spring on the spring seat, and a truck frame on the springs having yokes embracing the axle boxes.

5. In a car truck, the combination with the axle and axle boxes, a pair of links at each side of the axle boxes, a spring seat carried by said links, springs on said spring seats, a truck frame on said springs having yokes embracing the axle boxes, and means in the connection of said links with the axle boxes and with the spring seats for permitting a relative swinging or pivotal movement between the parts.

6. In a car truck, the combination with the axle and axle boxes, a projection extending out from each side of the axle boxes, each projection carrying a link pivotally secured thereto, a spring seat movably supported on said link, a spring on the seat, and a truck frame on the springs having a yoke operatively engaging the axle boxes.

7. In a car truck, the combination with an axle and axle boxes thereon, a plurality of projections extending outwardly from the axle boxes, each projection carrying a link, a spring-seat supported by each pair of links at each side of the axle boxes, a spring on the spring seats, and a truck frame on said springs having yokes embracing the axle boxes.

8. In a car truck, the combination with an axle having axle boxes thereon, a truck frame having yokes embracing the axle boxes, projections from the axle boxes at each side of the truck frame, a link depending from the said projections, a spring seat uniting said links into pairs at each side of the axle boxes below the truck frame, and a spring interposed between said spring seat and said truck frame.

9. In a car truck, the combination with an axle and axle boxes, of a truck frame having yokes embracing the axle boxes, projections extending outwardly from each side of the axle boxes, links pivotally supported on said projections and depending therefrom, spring seats movably connected with the said links so as to provide for a relative movement therebetween, and a spring interposed between said spring seats and the truck frame.

10. In a car truck, the combination with an axle and axle boxes, a truck frame having yokes embracing the axle boxes, spring seats diagonally disposed with relation to

the longitudinal axis of the axle, projections from said axle boxes, means for supporting said spring seats from said projections, and a spring interposed between each of said seats and the truck frame.

11. In a car truck, the combination with an axle and axle boxes, a truck frame having yokes embracing the axle boxes, spring seats diagonally disposed with relation to the longitudinal axis of the axle, projections from said axle boxes, means for supporting said spring seats from said projections, a spring interposed between each of said seats and the truck frame, and pivotal and movable connections between the projections and the spring seat.

12. In a car truck, the combination with the axle and axle boxes, a truck frame having yokes embracing the axle boxes, a pair of spring seats disposed below the truck frame with their longitudinal axes converging toward the axle, means for supporting said spring seats from the axle boxes, and a spring interposed between said seats and the truck frame.

13. In a car truck, the combination with the axle and axle boxes, a truck frame having yokes embracing the axle boxes, a pair of spring seats disposed below the truck frame with their longitudinal axes converging toward the axle, movable means for supporting said seats from the axle boxes, and a spring interposed between said seats and the truck frame.

14. In a car truck, the combination with the axle and axle boxes, a truck frame having yokes embracing the axle boxes, a pair of spring seats disposed below the truck frame with their longitudinal axes converging toward the axle, a pair of diagonally disposed links for supporting said seats from the axle boxes, and a spring interposed between said seats and the truck frame.

15. In a car truck, the combination with the axle and axle boxes, a truck frame having yokes embracing the axle boxes, a pair of spring seats disposed below the truck frame with their longitudinal axes converging toward the axle, a pair of diagonally disposed links movably supported from the axle boxes and movably connected with said spring seats, and a spring interposed between said seats and the truck frame.

16. In a car truck, the combination with the axle and axle boxes thereon, a truck frame having yokes operatively engaging the axle boxes, projections from the axle boxes at each side of the truck frame, links suspended from said projections, spring seats supported from said links below the truck frame, and springs interposed between said seats and the truck frame.

17. In a car truck, the combination with the axle and axle boxes thereon, a truck

- frame having yokes operatively engaging the axle boxes, projections from the axle boxes at each side of the truck frame, links pivotally suspended from said projections, 5 spring seats movably supported from said links below the truck frame, and springs interposed between said seats and the truck frame.
18. In a car truck, the combination with 10 an axle having axle boxes, a truck frame having a yoke operatively engaging the axle boxes, projections extending from the axle boxes at each side thereof, links supported from each of the projections, a spring seat 15 supported by said links below the truck frame, and a spring interposed between the seats and the truck frame.
19. In a car truck, the combination with 20 an axle having axle boxes, a truck frame having a yoke operatively engaging the axle boxes, projections extending from the axle boxes at each side thereof, links pivotally supported from each of the projections, a 25 spring seat movably supported by said links below the truck frame, and a spring interposed between the seats and the truck frame.
20. In a car truck, the combination with 30 the axle and axle boxes, a truck frame having a yoke embracing the axle boxes, a plurality of projections of different lengths 35 extending outwardly from each side of the axle boxes, links pendant from each of the projections, spring seats supported by said links below the truck frame, and a spring interposed between said links and seats.
21. In a car truck, the combination with 40 the axle and axle boxes, a truck frame having a yoke embracing the axle boxes, a plurality of projections of different lengths extending outwardly from each side of the 45 axle boxes, links pivotally pendant from each of the projections, spring seats movably supported by said links below the truck frame, and a spring interposed between said links and seats.
22. In a car truck, the combination with 50 the axle and axle boxes, a truck frame having yokes embracing the axle boxes, short projections extending outwardly from each side of the axle boxes inside the truck frame, longer projections extending outwardly from the axle boxes outside of the truck frame, links pendant from said projections at different distances from each side of the
- axle boxes, a spring seat supported by said links below the truck frame, and a spring interposed between said seats and the truck frame.
23. In a car truck, the combination with 55 the axle and axle boxes, a truck frame having yokes embracing the axle boxes, short projections extending outwardly from each side of the axle boxes inside of the truck frame, longer projections extending outwardly from the axle boxes outside of the truck frame, links pivotally pendant from 60 said projections at different distances from each side of the axle boxes, a spring seat movably supported by said links below the truck frame, and a spring interposed between said seats and the truck frame.
24. In a car truck, the combination with 65 the axle and axle boxes, a top chord, an axle box frame having yokes embracing the axle boxes, car supporting springs interposed 70 between the top chord and axle box frame, projections extending outwardly from each side of the axle boxes, a pair of pendant links supported by said projections at each side of the axle box frame, spring seats supported by said links, a spring interposed 75 between said seats and the axle box frame, a lower chord, and spring-posts uniting the upper and lower chords and axle box frame together.
25. In a car truck, the combination with 80 the axle and axle boxes, a top chord, an axle box frame having yokes embracing the axle boxes, car supporting springs interposed 85 between the top chord and axle box frame, projections extending outwardly from each side of the axle boxes, a pair of pendant links forming a stirrup supported by said 90 projections at each side of the axle box frame, spring seats supported by said stirrups, a spring interposed between said seats and the axle box frame, a lower chord, and spring posts passing through the car supporting 95 springs, the axle box frame, the stirrup spring and spring seat and secured to the top and lower chords.

Signed at Philadelphia, county of Philadelphia, State of Pennsylvania, this 14th day of August, 1912.

WALTER S. ADAMS.
